UNITED STATES PATENT OFFICE.

HEZEKIAH C. WELCH, OF HAVERHILL, MASSACHUSETTS.

SHOE.

No. 799,814.

Specification of Letters Patent.

Patented Sept. 19, 1905.

Application filed January 16, 1905. Serial No. 241,166.

To all whom it may concern:

Be it known that I, HEZEKIAH C. WELCH, of Haverhill, county of Essex, State of Massachusetts, have invented an Improvement in 5 Shoes, of which the following description, in connection with the accompanying drawings, is a specification, like characters on the drawings representing like parts.

This invention relates to certain improvements in that class of shoes known as "high-cut" shoes, and has for its object to provide a high-cut shoe which is adapted to be placed upon the foot and secured with the ease and facility of a low-cut shoe and is adapted to fit 15 the ankle of the wearer closely above the point at which it is secured by fastenings. I accomplish this object by means shown in the accompanying drawings, in which—

Figure 1 shows in side elevation, and Fig. 20 2 in front elevation, a shoe made according to my invention.

The shoe illustrated is provided with quarter-pieces *a a*, which extend from the vamp *b* upwardly to the top of the shoe, the edges of 25 the quarter-pieces in front being approximately parallel and meeting or nearly meeting from a point at the middle of the vamp to a point approximately half-way to the top of the shoe or just above the instep and providing an 30 opening to be laced, the edge portions of the quarters adjacent said opening being provided with eyelets having a lacing *c* therein.

The quarter-pieces are so formed that their edges diverge from the upper end of the lacing-opening and extend about and toward the back of the shoe nearly horizontally for a short distance and then extend divergently upwardly to the top thereof. The upwardly-extending edges are equidistant from the middle 35 line of the shoe and are joined by an elastic goring *d*, which is sewed thereto. The upper end of the goring *d* is continuous with the upper edge of the quarters, and its lower end terminates at a short distance above the 40 lacing-opening or the horizontally-running edges of the quarters, so that a finger-aperture *e* is provided therebetween. A tongue *f* extends from the vamp upward across the opening *e* and terminates a short distance 45 above the lower end of the goring.

In placing the shoe upon the foot the lacing

is loosened and the laced edge portions are separated, and then the shoe is preferably drawn on the foot by inserting the fingers in the opening *e* and pulling on the tongue and on the 55 loop at the back of the shoe simultaneously, the elastic goring *d* permitting the foot to pass through the upper portion of the shoe. The lacing is then drawn tight and tied. The upper end of the tongue *f* is tucked in under 60 the goring, the opening *e* enabling the wearer to do this conveniently, as well as enabling him to pull on the tongue conveniently in drawing on the shoe or to pull the tongue up into position. The uppermost eyelets are 65 closely adjacent the opening *e*, so that the bow-knot in the lacing will cover the opening to a considerable extent. When the shoe is to be removed, the knot in the lacing is untied, and then the wearer may insert his fingers in the 70 opening *e*, grasp the edge portions of the quarters between the lacing and goring, and pull them apart as easily as if the goring were not employed—that is, the goring is so located that it closes the main portion of the shoe-opening 75 above the lacing and yet does not interfere with the fastening or unfastening of the shoe, this being accomplished as readily as if the shoe were an ordinary Oxford.

The above-described shoe possesses practically the most desirable advantages of both a high and a low cut shoe without the disadvantages of either, as the shoe has the appearance of an Oxford in front and may be secured to the foot with as little or even less difficulty 85 than an Oxford, and yet is in reality a high shoe. The shoe can be manufactured at practically the same cost as an ordinary shoe.

Having thus described my invention, what I claim as new, and desire to secure by Letters 90 Patent, is—

A shoe comprising quarter-pieces extending from the vamp to the top, the front edges of said pieces being equidistant from the middle of the front of the shoe, the lower portions of 95 said edges extending adjacent and approximately parallel to each other, and a lacing for drawing them together, said edges extending divergently about the shoe from the upper ends of said laced portions and then upwardly 100 to the top of the shoe, an elastic goring connected to said upwardly-extending edges and

closing the space therebetween from the top to within a short distance of said diverging portions, providing a finger-aperture therebetween, and a tongue connected to the vamp, 5 and extending to said finger-aperture, substantially as described.

In testimony whereof I have signed my name

to this specification in the presence of two subscribing witnesses.

HEZEKIAH C. WELCH.
